UNITED STATES PATENT OFFICE.

WILLIAM D. YOCUM, OF WETUMKA, OKLAHOMA.

DEVICE FOR JOINING RAILS.

1,405,886.

Specification of Letters Patent. Patented Feb. 7, 1922.

Application filed July 30, 1921. Serial No. 488,665.

To all whom it may concern:

Be it known that I, WILLIAM D. YOCUM, a citizen of the United States, residing at Wetumka, in the county of Hughes and 5 State of Oklahoma, have invented certain new and useful Improvements in Devices for Joining Rails, of which the following is a specification.

This invention relates to improvements in 10 devices for joining rails and has as its object to provide a device for this purpose which will serve effectually to unite the meeting ends of aligned rails and securely hold the same in alignment and against spreading, 15 or overturning.

Another object of the invention is to provide a device of the class described which will automatically adapt itself to the rails when it is adjusted for clamping engagement 20 with the rails, it being only necessary to manipulate a single element of the device in order to adjust the rail clamping members of the same so as to cause them to clamp and suitably space the rails to which they 25 are applied and prevent spreading and overturning.

Another object of the invention is to provide a device for the purpose stated so constructed that the same may be readily and 30 quickly adapted to the rails, and as readily removed therefrom when occasion requires.

In the accompanying drawings:

Figure 1 is a top plan view of the device embodying the invention.

Figure 2 is a vertical longitudinal, sectional view therethrough.

Figure 3 is a perspective view of one of the rail clamping heads.

Figure 4 is a vertical transverse sectional view taken substantially on the line 4—4 of Fig. 2.

In the drawings the rails to be joined are indicated by the numeral 1 and as will be observed by reference to Figure 1 of the 45 drawings, the device embodying the invention is to have one of its clamping heads applied to the meeting ends of two rails at one side of the track and its other clamping head applied to an intermediate portion of 50 the opposite rail so that the said meeting ends of the two first mentioned rails will not only be firmly clamped and maintained in mutual alignment, but also these ends of the said rails will be prevented from spread-

ing out of parallelism to the opposite rail 55 and also prevented from overturning.

The device embodying the invention comprises a pair of clamping heads and means connecting the heads and operable to relatively adjust the clamping members thereof. 60 These heads are indicated in general by the numeral 2 and each comprises a body 3 provided at its outer end and at its upper side with a transversely extending rail clamping jaw 4 which is shaped for engagement 65 against the outer side of the web and base flange against which the member is disposed as best is shown in Figure 2 of the drawings. Each rail clamping head further comprises a movable jaw member which is indicated by the numeral 5 and which is likewise shaped to embrace the inner side of the base flange and web of a rail. The jaw member 5 is formed upon its inner side midway between its ends with a downwardly 70 projecting boss 6 formed with a dove-tailed recess 7 which is adapted to receive beveled ribs 8 formed longitudinally of the upper side edges of the body 3 of the clamping heads, the under-cut walls of the recess 7 80 engaging beneath the said beveled ribs 8 so as to provide an interlocking engagement between the clamping jaw 5 and the body 3 and to establish a slidable connection between these parts so that the said jaw member 4 may be slidably adjusted with relation to the respective jaw member 5. 85

In order to provide for assemblage of the jaw member 5 with the body 3 and to likewise provide for operation of these parts, 90 the ribs 8 are cut away as at 9 for a suitable portion of their length and at their ends remote from the fixed jaw member 4, so that when the jaw member 5 is slid to position with its boss 6 located at the point where 95 the ribs are cut away, the said member 5 may be lifted out of engagement with the body 3. However when this member is in locking engagement with the ribs 8, the parts will be securely united and held 100 against relative movement except that incident to the adjustment of the jaw member 5.

In order that the members 4 of the two clamping heads may be simultaneously adjusted and be brought into clamping engagement with the rails to be joined, the relatively adjacent ends of the bodies 3 of the two heads are formed with upstanding 105

bosses 10 each provided with a threaded bore 11, and a turn buckle rod 12 has its oppositely threaded end portions adjustably fitted through the bores 11. The opposite extremities of this rod are somewhat reduced in diameter as indicated by the numeral 13 and are rotatably received in sockets 14 formed in the adjacent sides of the jaw members 5. In order that the rod 12 may be rotatably adjusted, it is formed intermediate of its ends with a preferably cylindrical head 15 having a circumferential series of sockets 16 for the reception of a bar which is to serve as a lever for the purpose stated.

15 From the foregoing description of the invention it will be seen that there is provided a rail joining device so constructed that in the adjustment of a single element thereof, namely the turn buckle rod 12, the movable 20 jaws of the two clamping heads are respectively drawn into engagement with the outer sides of the rails so that these members are caused to firmly clamp the respective rails with which they are engaged.

25 Having thus described the invention, what is claimed as new is:

1. A device of the class described embodying a pair of rail clamping heads each comprising a body, a fixed clamping jaw carried thereby, spaced ribs upon the body interrupted for a portion of their length, a

clamping jaw slidable upon the body with relation to the fixed jaw and having means for inter-locking engagement with the ribs, the said movable jaw, when moved to position with the said means thereof located at the point of interruption of the ribs upon the body, being separable from the body, and means cooperating with the bodies of the two heads and with the movable jaws thereof to relatively adjust the bodies and the said jaws respectively.

2. A device of the class described embodying a pair of rail clamping heads each comprising a body, rail engaging jaws at the relatively remote ends of the two bodies, upstanding bosses at the relatively adjacent ends of the two bodies, the said bosses being provided each with a threaded bore, a rail clamping jaw having slideable connection with the upper side of each of the said rail clamping heads between the clamping jaw thereof and the boss, and a turn buckle rod having its oppositely threaded end portions fitted through the bores of the bosses and having swivel engagement at its ends with the last mentioned clamping jaws, the head of the turn buckle rod being located between the said relatively adjacent ends of the said rail clamping heads.

In testimony whereof I affix my signature.
WILLIAM D. YOCUM.
